FRANZ KREMSKI AND HERMAN SIEMERING, OF NEW YORK, N. Y.

TIE FASTENER.

Application filed March 7, 1927. Serial No. 173,375.

This invention relates to tie fasteners, and has for its particular object to provide a simple and efficient clasp for fastening the tie to the shirt front. Another object is to make possible the wearing of one of these clasps without attracting undue attention by applying it underneath the tie itself, thereby rendering the clasp invisible. A further object is to provide means for easily applying the tie fasteners to the tie. A still further object is to make the fastener adaptable to a number of ties at a very low cost. Still further objects will appear in the following specification and the accompanying drawings 15 in which

Fig. 1 is a fragmentary perspective view showing a shirt front and a tie, the lower half of which is fastened to the shirt by a clasp, the upper half being partly turned over to 20 disclose its fastening means;

Fig. 2 is a longitudinal horizontal sectional view through the shirt clasp and tie fastener;

Fig. 3 is a bottom view of the clasp;

Fig. 4 is a sectional view similar to Fig. 2, 25 but showing the clasp and tie fastener apart from each other, prior to being fastened together;

Fig. 5 shows the two component parts of the tie fastener before being fastened to the 30 tie;

Fig. 6 is a sectional view of a modified form of a tie fastener in which the two component parts are made of one piece; and

Fig. 7 is a plan view of such fastener, prior 35 to being bent over to be secured to the tie.

Like numbers of reference denote similar parts throughout the several views and the following specification.

10 is a male part of a fastener consisting of 40 a disc 11 having a shank 12 which is, preferably, drawn from the disc. The shank 12 has a pointed end portion 13 and a slightly reduced neck 14 between the end portion 13 and the disc 11. 15 is a female part of the fastener, comprising substantially a disc 16 similar to disc 11 and a rounded button 17, also drawn from the disc, and forming within it a socket 18 having a mouth 19 somewhat smaller than its largest portion. 19^a are slots 45 within the walls of the button to impart to it a certain degree of elasticity. Both of parts 20 and 15 are, preferably, but not necessarily, made of sheet metal. 20 is a tie comprising

an upper half having an outer layer 20^a and an inner layer 20^b, and 20^c is a lower half of 55 the tie.

21 is a clasp comprising a disc 22 having a tubular projection 23 drawn from it which has a shoulder 24 around its inner top. 25 is a lateral extension from the disc 22 having 60 two lugs 26 projecting at right angles thereto supporting a pivot pin 27 between them. 28 is an operating handle, having two depending lugs 28^a pivotally mounted upon pin 27 between lugs 26. 29 is a spring coiled around pin 27 having one end resting on extension 25 and its other end on handle 28, forcing the same apart, and one end of the handle bar 65 against a shirt 30 and lower half 20^c of the tie 20 between them. 70

In applying our fastener to the tie, the male part 10 with its pointed terminal 13 is pushed through the fabric of the inner layer 20^b of the upper half of the tie 20, and the socket 18 of the female part 15 is snapped 75 over this pointed end, the reduced mouth 19 snugly fitting the neck 14 holding it securely in such position. The clasp 21 is then slipped over an edge of the shirt front and the lower half 20^c of the tie 20, as clearly shown in 80 Figs. 2 and 4, and is now ready for the reception of the tie fastener 10 and 15. The projecting button 17 of part 15 is then pressed

into tubular projection 23 of the clasp and held there by the shoulder 24. Thus it will 85 be seen that the fastening device consists of essentially two units, viz a tie fastener, the details of which are shown in Fig. 5, which is secured to the upper part of the tie, and the clasp which is fastened to the shirt front and the lower part of the tie. These two 90 units are then connected together in a simple manner similar to fastening a glove, the front half of the tie covering the laterally projecting clasp, thereby rendering it invisible. 95

In using our invention, a number of ties may each be permanently equipped with fasteners 10 and 15 and used with the same clasp. This feature lends itself particularly well to the commercial exploitation of the invention, because it can be merchandised on cards containing one clasp and a number of fasteners, the latter being subject to repeat orders. 100

In the modified form of tie fastener shown in Figs. 6 and 7, the discs 11 and 16 are joined 105 together by a narrow bridge 31 which is suffi-

ciently flexible to be bent into shape for attaching to the tie, as more particularly shown in Fig. 6. This modification is preferred in so far as it is possible to reduce the number of parts of the fastener and more conveniently market them on cards, as stated above, the function of each disc and their method of co-operation being identical to the one above described.

10 While we have shown and described the parts of the device made of sheet metal, other materials with self-evident changes in the construction may be employed. Instead of slots 19^a to give elasticity to the button 19, 15 many other means, well known in the art, may be used for the same purpose. The form of the clasp is intended to illustrate only a prevailing method of fastening the disc 22 to the shirt and tie, and we wish not to be limited 20 to the particular style shown, but any other clasp, separate from or integrally connected to the disc may be used.

It is obvious that many other changes in the proportion and constructive details may 25 be resorted to without sacrificing any of the advantages or principles of the invention as set forth in the appended claims.

What we claim as new, is:

1. Tie fastening means comprising a disc 30 having a pointed shank adapted to pierce the inside layer of the front flap of a tie, a companion disc having a socket for the reception of the said pointed shank, a clasp removably attached to a shirt and the back flap of the 35 tie, and means to detachably secure the said companion disc to the said clasp.

2. Tie fastening means comprising a disc having a shank terminating in a point and having a reduced neck, a companion disc having a socket for the reception of the said pin,

the mouth of the socket being reduced to fit the said neck, both discs adapted to clamp the inside layer of the front flap of a tie between them, a clasp removably attached to a shirt and the back flap of the tie, the said companion disc having means to fasten the disc to the said clasp. 45

3. Tie fastening means comprising a disc having a pointed shank adapted to pierce the inside layer of the front flap of a tie, a companion disc having a socket for the reception of the said shank and a button, a clasp removably attached to a shirt and the back flap of the tie having a socket, the said button being adapted to be detachably secured to the said 55 socket.

4. Tie fastening means comprising a disc having a pointed shank adapted to pierce the inside layer of the front flap of a tie, a companion disc hingedly connected to the said 60 first named disc and having a socket for the reception of the said pointed shank, a clasp removably attached to a shirt and the back flap of the tie, and means to detachably secure the said companion disc to the said clasp. 65

5. Tie fastening means comprising a pair of discs made of a single piece of sheet metal and fastened together by a narrow bridge, adapted to be squeezed together to hold between them the inside layer of the front flap 70 of a tie, a clasp removably attached to a shirt, and means to detachably secure the said discs to the said clasp, one of the said discs having a pointed shank adapted to pierce the said tie and the other disc having 75 a socket for the reception of the said shank.

In testimony whereof we have hereunto set our hands.

FRANZ KREMSKI.
HERMAN SIEMERING.
